UNITED STATES PATENT OFFICE.

CLINTON O. HARRINGTON, OF CHICAGO, ILLINOIS.

ELECTRICAL INSULATOR.

1,386,863.

Specification of Letters Patent. Patented Aug. 9, 1921.

Application filed April 8, 1920. Serial No. 372,345.

To all whom it may concern:

Be it known that I, CLINTON O. HARRINGTON, a citizen of the United States, and a resident of Chicago, in the county of Cook 5 and State of Illinois, have invented certain new and useful Improvements in Electrical Insulators, of which the following is a specification.

My invention relates to electrical insulators. Its prime object is to provide an insulator having peculiar strength and durability. A specific object is to provide an insulator device having such properties in 10 situations where the parts to be insulated 15 from each other have relative movement which gives rise to a grinding action. Other important objects are to provide an insulator of such construction that its several elements or parts may be easily and thoroughly treated to provide them with desirable 20 insulating properties; which may be easily shaped for particular uses; which may be readily assembled for use; which in some forms may have a relatively small amount 25 of insulating material while providing a high degree of durability and the desired degree of electrical resistance. Other objects and advantages will appear herein-after.

In the accompanying drawings, which 30 form a part of this specification Figures 1 to 15 inclusive are fragmentary vertical cross sections showing in enlarged form the thickness of insulator elements or devices 35 according to my present invention, and Fig. 16 is a cross section of a railway rail, with fish plates and forms of my new insulating device operatively positioned between the plates respectively and the rail.

The plates, strips, etc., of Figs. 1 to 15 40 may be of any desired length and width according to particular uses, and of thickness also to a large extent, although for such uses as the rail joint insulation shown the several 45 parts respectively will be relatively thin.

In many situations where electrical resistance is desired between two metallic parts much difficulty has been experienced owing 50 to the fact that weather conditions, and the pressure imposed upon the insulating material cause the insulation to disintegrate and fail. In some situations too, for instance at rail joints in railway practice, the parts to be insulated have some relative movement 55 to each other which causes a grinding action upon the interposed insulation wearing it

away and causing it to fail. In the railway practice mentioned the track rails constitute electrical conductors for operating the block signals, it being necessary to insulate from 60 each other sections of the track at intervals, all as is well understood. The importance of a form of insulation at these rail joints which will be notably free from the effect of the abrasive or other disintegrating forces 65 found under conditions of service is apparent, and I have chosen this application of my improved insulator for illustration herein as an important example of its advantageous use.

Referring further to the drawings, Fig. 1 shows an insulator unit comprising a metallic part 20 having an electrical insulating coating 21 on one side surface thereof.

Fig. 2 shows a unit having a metallic plate 75 22 with an insulating coating 23 on both sides and around the edges thereof.

Fig. 3 shows a plurality of metallic plates 20 each having an insulating coating 21 on one side thereof. This figure shows three 80 of the plates of Fig. 1 in laminated arrangement.

Fig. 4 shows three of the plates of Fig. 2 in laminated arrangement.

In Fig. 5 there are three metallic plates 85 24 and insulating material 25 in sheet form between them. The insulation 25 is shown as extending beyond the plates partly for the purpose of clearness of illustration and partly to show a construction in which the 90 electrical current or static charge is prevented from jumping around the ends of the insulation from one plate to the other, should the charge come upon one or both of the outside plates.

Fig. 6 shows a plurality of the units of Fig. 2 with insulation material 25 in sheet form between the contiguous units 22-23.

In Fig. 7 there are two oppositely disposed elements 27 which it is desired to insulate 100 from each other, with the unit of Fig. 2 between them.

Fig. 8 shows an insulator unit comprising a strong foraminous reinforcing element 28, which may be wire mesh, and is so shown, 105 with insulating material 29 embedding the mesh.

Fig. 9 shows a similar construction to that of Fig. 8, but the inner member 30 is to be considered as of textile fabric, such as 110 canvas for instance, with the insulating material 31 laid upon the sides of the fabric,

For coating the fabric it may be dipped into liquid insulating material and allowed or caused to harden.

Fig. 10 shows two of the units of Fig. 8 5 or Fig. 9 on opposite sides of a smooth metallic plate 32, and upon these insulating units respectively are placed the members 33 which it is desired to insulate from each other.

10 In Fig. 11 there is a smooth metallic plate 35 and on its opposite sides is placed insulating material 36 in sheet form, which may be considered as of fiber, celluloid, mica, etc., and on the outer sides respectively of the 15 parts 36 there are the members 37 to be insulated from each other.

10 In Fig. 12 the parts 38 which it is desired to insulate from each other are shown as having a serrated or roughened surface facing 20 insulation material 21 upon the plates 20, this figure showing two of the units of Fig. 1. The plates 20 are smooth on their surfaces facing each other and will slide upon each other when relative movement occurs 25 between the parts 38.

In Fig. 13 there are two smooth plates 39 with insulating material 40 between them, the wear or service plates 41 being next to the smooth plates 39 so as to slide upon 30 them.

10 In Fig. 14 the service plate 42 lies upon a smooth plate 43 which lies upon insulating material 44 which is next to two smooth plates 45 followed by an insulating element 35 46, which is succeeded by a smooth plate 47, this being followed by insulation 48, and finally there is the opposite plate or service element 49. The plate 42 may slide upon the plate 43 and the plates 45 may also slide 40 upon each other, and the insulating material may also slide upon the adjacent plates.

10 In Fig. 15 there is a service plate 50, insulation 51, three smooth plates 52, another insulating element 53, another smooth plate 45 54 and finally the other service plate 55.

10 The electrical insulation material which constitutes the coating on one or more of the surfaces of the metallic strips, sheets, plates or elements may be any of the well known insulating materials available for 50 coating metallic parts such, for instance as varnish, enamels, japan, shellac, glazes, as well as other substances which may from time to time be found available for such purposes. The coating may also be such as is produced by chemical action in which the surface of the metallic elements is transformed, for instance by the formation of an oxid or other chemical compound having 55 the property of electrical resistance, or, electrolytically, by depositing a surface coating upon the metallic part. The invention is not limited to any particular kind of insulating covering or coating upon the metallic 60 parts.

10 By the term electrical insulation in sheet form I mean such materials as mica, celluloid and the like, varnished or otherwise coated textile or other fabric, fiber, paper, rubber, etc., having in mind all materials 70 and substances in sheet form which in particular applications may be found suitable. A large variety of these is well known.

10 In Fig. 16 the rail 60, fish plates 61 and 62, the bolt 63 and the insulating tube or bushing 64 for the bolt are according to well known practice. It is also well known practice to place insulating material between the rail 60 and the fish plates. Owing to the character of the foundation for the rails and 80 to the wave-like motion of the rails under the heavy rolling stock, and due to the sudden shifting of the load from one rail to the other at the rail joint, the two rails have relative movement between the fish 85 plates and the rails. The rail and the fish plates have comparatively rough surfaces where they face each other, owing to the methods of construction employed, and where, according to prior practice, sheet-form insulation is placed directly between these elements it is soon worn away.

10 The insulation 65 of Fig. 16 is to be considered as in accordance with Fig. 12 in which the outer members 38 may be considered the equivalent of the rail and fish plate respectively, the insulation device consisting of two of the plates of Fig. 1, these plates being smooth on their sides facing each other and being adapted to slide upon 100 each other when the fish plate and rail move relative to each other. The insulation 66 of Fig. 16 may be considered to be in accordance with Fig. 13 of the drawings in which the wear plates 41 may be considered the equivalent of the rail 60 and the fish plate 62, there being a smooth plate adjacent to the fish plate and another smooth plate adjacent to the rail, with insulating material 40 between these two smooth plates. It is to 110 be understood, however, that the laminated construction shown by the other figures may be used where a metallic element is part of the insulator device. Various other combinations of the laminae may also be adopted.

10 The relative movement of the fish plates and rail is relatively slight where the bolts are suitably tightened, but it is persistent, and the tendency to grind may take place over most of the surface of the insulation. 120 In some cases the wear is limited chiefly to particular localities, and, according to the present improvements where a plurality of insulating media are employed, while the wear may in time destroy one of the media 125 so that metallic parts will be there rubbing together, other media will be left intact and the effectiveness of the insulation be thus preserved.

10 The smooth plates referred to herein may 130

be fairly thin, such as ordinary tin plate or copper sheet material of say 18 to 24 gage. In coating these plates they may conveniently be dipped in the soft insulating material and then either baked or hardened in the air according to the character of material employed.

Some well known insulation materials suitable for such purpose do not crack or break when the metal to which they are applied is bent even at sharp angles. My improved form of insulator device may therefore have its several parts cut to the desired length and width, the parts laid upon each other in laminated form and by pressing them in a die the entire device may be given its desired shape, as for instance that of the insulators 65 and 66 of Fig. 16.

An important advantage of the laminated construction employing relatively thin plates is in the flexibility which it gives the device as a whole in situations of relative movement between the parts to be insulated from each other. Thus when strains occur tending to bend the insulation as a whole the thin laminations slide upon each other and adjust themselves to the bent condition without breaking, each lamina bending individually as a unit; and, where the insulating material has a smooth surface to slide upon the wear is very slight, making for long life in service.

Another important advantage is that relatively thin sheets of paper, fabric, etc., may be more thoroughly impregnated with insulating compounds than is possible with the thicker sheets customarily employed, rendering them less likely to absorb moisture and consequently reducing swelling and softening of the sheets. Insulation so formed is also less compressible, and this coupled with its merely slight expansion due to moisture eliminates in large part the trouble experienced with fiber insulation, which swells due to the absorption of moisture and on shrinking leaves the joint loose, thereby greatly increasing the wear due to increased relative movement of the several parts at the joint.

A further feature of advantageous construction is to dip some or all of the laminæ in melted paraffin or the like, either before or after the laminæ of the insulator device are assembled. Such a substance not only aids in water-proofing the device and its elements but, importantly, it acts as a lubricant between the laminæ inducing more ready slippage. In the drawings insulators 65 and 66 are to be considered as having the several laminæ so treated.

While I have referred herein to the plates 20, 22, 32, etc., as "metallic" the invention is not limited to metal in this respect, as, in some applications such substantially hard and smooth materials as hard pressboard,

celluloid, etc., may be used. Various other changes may be made without departing from the spirit of my invention, and I contemplate all such departures as fall within the scope of the appended claims.

70

I claim:

1. The combination with a pair of oppositely disposed members to be insulated from each other and having movement with respect to each other, of an insulator device between said members comprising a metallic element having a smooth surface on which a facing and contiguous member may freely slide and a layer of insulating material facing and contiguous to said metallic element. 75

2. The combination with a pair of oppositely disposed members to be insulated from each other and having movement with respect to each other, of an insulator device between said members comprising a thin metallic sheet having a smooth surface on each side thereof and insulating material contacting said surfaces and adapted to slide thereon. 80

3. The combination with a pair of oppositely disposed members to be insulated from each other and having movement with respect to each other, of an insulator device between said members comprising a plurality of smooth metallic plates some of which 95 contact and are adapted to slide upon each other, and insulating material between said pair of oppositely disposed members. 90

4. An electrical insulator device comprising a pair of oppositely disposed metallic elements, their facing surfaces being rough and adapted to hold insulating material firmly, a smooth metallic element between said other metallic elements, and insulating material between said smooth plate and said 105 rough-surfaced elements respectively.

5. A laminated electrical insulator device comprising insulating material and a smoothly surfaced sheet on which the insulating material may slide. 110

6. The combination with parts to be insulated from each other and having relative movement with respect to each other of an electrical insulator device comprising laminæ free to slide one upon another. 115

7. In combination, a rail, a fish plate or the like at one side thereof, and between the fish plate and the rail an insulating device comprising laminæ free to move one upon another, and means for holding the 120 rail, insulator and fish plate together.

8. In combination, a rail, a fish plate, and between them an insulating device comprising laminæ, one thereof being insulating material, another thereof being a hard and smooth-surfaced element adapted for slippage action relative to a facing contiguous member, and means for holding the fish plate, insulator and rail together. 125

9. In combination, a rail, a fish plate or 130

the like, and between them an insulator device in laminated form, one lamina being insulating material and another thereof being metallic, the contiguous laminæ being free to move upon each other, and means for holding the fish plate, insulator and rail together.

10. In combination, a rail, a fish plate, and between them an insulator device comprising insulating material and substantially hard and smooth slippage elements in alternate arrangement, and means for holding the fish plate, insulator and rail together.

11. In combination, a rail, a fish plate, and between them a laminated insulator device including substantially smooth and hard elements adapted to slide one upon another, and means for holding the fish plate, insulator and rail together.

20. 12. In combination, a rail, a fish plate, and between them an insulator device com-

prising a laminated structure having a plurality of insulating laminæ and a substantially hard and smooth element adapted to provide ready slippage constituting one of 25 the laminæ, and means for holding the fish plate, insulator and rail together.

13. An electrical insulator device comprising a metallic plate having a roughened surface, insulating material in sheet form facing 30 and contiguous to said surface, and a relatively thin and smooth metallic plate facing and contiguous to said insulating material, the smoothness of said plate being adapted to promote slippage between it and the insulation.

14. In combination, a rail, a fish plate, and between them an insulator comprising laminæ, one of the laminæ being coated with a substance having the property of promoting 40 slippage between the laminæ.

CLINTON O. HARRINGTON.
